OUTER TUBE FOR A TAMPON INSERTER

Alfred R. Thomas, Wyoming, and Darrel D. Koxx, Greenhills, Ohio, assignors to The Procter & Gamble Company, Cincinnati, Ohio

Filed Feb. 18, 1970, Ser. No. 21,492

Term of patent 14 years

Int. Cl. D24—99; D28—01

U.S. Cl. D83—12

FIG. 1

FIG. 1 is a side elevational view of an outer tube for a tampon inserter showing our new design.

FIG. 2 is an end elevational view of the same as seen from the top of FIG. 1.

FIG. 3 is an end elevational view of the same as seen from the bottom of FIG. 1.

We claim:

The ornamental design for an outer tube for a tampon inserter, as shown.
